United States Patent Office

Des. 225,327
Patented Dec. 5, 1972

225,327

WATER SOFTENER CABINET

William J. Marsh, Garden Grove, Calif., assignor to
Robert Marsh Enterprises, Inc., Santa Ana, Calif.

Filed May 5, 1971, Ser. No. 140,640

Term of patent 14 years

Int. Cl. D23—01

U.S. Cl. D23—3

FIG. 1 is a perspective view of a water softener cabinet showing my new design;

FIG. 2 is a top plan view thereof; and

FIG. 3 is a bottom plan view thereof.

I claim:

The ornamental design for a water softener cabinet, as shown.
